UNITED STATES PATENT OFFICE

CARL KAUFMAN, OF NEW YORK, N. Y.

DESIGN FOR A BOOK END OR SIMILAR ARTICLE

Application filed January 30, 1931. Serial No. 38,505. Term of patent 14 years.

To all whom it may concern:

Be it known that I, CARL KAUFMAN, a citizen of the United States, residing in New York city, county of New York, and State of New York, have invented a new, original, and ornamental Design for a Book End or Similar Article, of which the following is a specification, reference being had to the accompanying drawing, forming part thereof.

The ornamental design is of a figure shown as on a base and which in addition to serving as a book end may serve manifold other uses such as, as a paper weight or as a toy.

The figure in the drawing is a perspective of my new design.

I claim as my invention:

The ornamental design for a book end or similar article as shown and described.

CARL KAUFMAN.
